P. M. GRIFFIN,
STEAM HOSE COUPLING.
APPLICATION FILED MAR. 25, 1919.

1,402,598.

Patented Jan. 3, 1922.

Inventor,
Percy M. Griffin,

By E. M. Bentley
ATTORNEY.

UNITED STATES PATENT OFFICE.

PERCY M. GRIFFIN, OF ALBANY, NEW YORK, ASSIGNOR TO CONSOLIDATED CAR-HEATING COMPANY, OF ALBANY, NEW YORK, A CORPORATION OF WEST VIRGINIA.

STEAM-HOSE COUPLING.

1,402,598.

Specification of Letters Patent.

Patented Jan. 3, 1922.

Application filed March 25, 1919. Serial No. 284,913.

To all whom it may concern:

Be it known that I, PERCY M. GRIFFIN, a citizen of the United States, residing at Albany, in the county of Albany and State of New York, have invented certain new and useful Improvements in Steam-Hose Couplings, the following being a full, clear, and exact disclosure of the one form of my invention which I at present deem preferable.

For a detailed description of the present form of my invention, reference may be had to the following specification and to the accompanying drawing forming a part thereof, wherein—

Fig. 1 is a side elevation and
Fig. 2 a plan view of my device.

My invention relates to a steam hose-coupler of the familiar Sewall type wherein a projection on one side of each part or member overlaps and interlocks with, under wedging pressure, a stud on the overlapped side of the opposite member, the wedging being aided by gravity.

On each part or member of such a coupler I pivot a latch which hooks over a stud on the opposite member and is locked by means of an eccentric sleeve or cam applied to the pivotal joint of the latch.

Referring to the drawing, A and B indicate the respective parts or members of a Sewall type coupler, the details of which are so well known that an illustration and description thereof is not needed.

My invention resides in certain L-shaped latches A² and B² jointed to the respective members. For this purpose the members are provided with pivot lugs A³, B³, to which the latches are jointed at their rear ends, and with studs A⁷, B⁷, which stand in front of and in line with the lugs A³, B³ and are engaged by the toes or offsets of the respective latches. The latches have pintles A⁴, B⁴ fast

thereon substantially parallel with the offset ends thereof and passing axially through sleeves A⁵, B⁵ which are journalled in the 45 lugs A³, B³ and are provided with rearwardly extending thumb levers A⁶, B⁶. The axis of each sleeve is eccentric to the axis of its corresponding pintle. The parts are secured together by heading-over the ends of the pintles, and are represented in the drawings in the locked position. By pressing up one of the thumb-levers—say B⁶—it is obvious that the rotation of sleeve B⁵ will throw the latch B² bodily to the right, thereby loosening its 55 grip on studs A⁷. The latch can then be easily lifted up and turned back to free the two members, the same being true of the latch, sleeve and lever on the opposite member. Conversely when it is desired to latch 60 the two members together B² will be turned down over the opposite stud A⁷ and the depression of the thumb-lever B⁶ will draw the latch to the left causing its toe to grip the stud A⁷ and the final pressure on B⁶ wedges 65 the eccentric sleeve in between pintle B⁴ and lug B⁵ to give the latches a frictional lock.

What I claim as new and desire to secure by Letters Patent is:

A Sewall-type coupler, comprising two 70 coupler members each provided with a locking stud and a bearing lug, thumb-levers having cylindrical portions rotatably mounted within said bearing lugs, and latches provided with pintles having eccentric engagement with the cylindrical portions of the respective thumb-levers, the latch of each member being shaped to engage the locking stud of the other member, said studs being positioned to stand in line between the locking 75 devices.

Signed at Albany, county of Albany, State of New York, this 21st day of March, 1919.

PERCY M. GRIFFIN.
